UNITED STATES PATENT OFFICE.

WILLIAM B. HOLT, OF ROSEMARY, NORTH CAROLINA.

SHUTTLE-BINDER.

1,316,551.

Specification of Letters Patent. Patented Sept. 16, 1919.

Application filed August 6, 1919. Serial No. 315,721.

To all whom it may concern:

Be it known that I, WILLIAM B. HOLT, a citizen of the United States, residing at Rosemary, in the county of Halifax and State of North Carolina, have invented certain new and useful Improvements in Shuttle-Binders, of which the following is a specification, reference being had to the accompanying drawings.

10 This invention relates to shuttle binders, and particularly to binders designed to work in connection with magazine looms having feeler motions.

15 The general object of my invention is to provide a very simple binder adapted to work in connection with the Crompton-Knowles magazine loom and on the Draper automatic loom, which will do-away with the necessity of check straps, binder springs, 20 etc., and whereby the loom may be run with less power, whereby the shuttle may be held in position so that there is no breakage of bobbins when the magazine makes its change and whereby neither damp nor dry weather 25 will affect the shuttle box when the binder is used.

And a further object is to provide a binder construction which will not cause the shuttle to "rebind" and which will hold the shuttle 30 parallel to the line of the back box, providing for a change of bobbins in magazine looms without any liability to breakage.

A further object is to provide a binder which will check the shuttle very gradually 35 at first and which then acts to offer more resistance to the shuttle, causing the shuttle to reach its destination without any rebind or bouncing, thus eliminating trouble given by all ordinary binders.

40 A further object is to provide a binder which, after the shuttle has reached its destination, will be pressed outward at the forward end by the shuttle, thereby pressing just sufficient on the middle of the shuttle 45 as to place the shuttle in parallel line with the back of the shuttle box so that the magazine mechanism has full chance to pass the bobbin through the shuttle on exchanging.

50 A further object is to provide a binder which will have a quick and easy release when the loom makes its pick, thus saving considerable power in operating the loom.

55 A further object is to provide a binder which may be easily adjusted to suit different sized shuttles and which will oper-

ate properly with the loom running at different speeds and which will operate steadily without the loom "banging off."

My invention is illustrated in the accompanying drawings, wherein:

Figure 1 is a top plan view of a portion of a lay beam and shuttle box with my binder applied thereto, the binder being broken away, and the shuttle being shown in its fully entered position.

Fig. 2 is a like view to Fig. 1, but showing the shuttle as it enters the box.

Referring to these drawings, 10 designates a lay beam with a stationary shuttle box 70 11, 12 designating the bolt and back piece connected to the lay beam, 13 the usual bolt in the back piece, 14 the shuttle box mouth piece next to the reed and bolted to the lay in the usual manner, 15 the lip on the mouth piece, and 16 the usual protector finger. The shuttle 17 is of the usual construction, 18 designating the bobbin spring, and 19 the shuttle eye. All of these parts are of any well known and ordinary character and require no special description.

The front binder 20 is formed of a casting, somewhat angular in form, to provide two arms 21 and 22, this binder being pivoted upon a vertical pivot pin at the intersection 85 of the arms, as at 23. This pivot pin passes through ears 24 on the box plate. The arm 21 is shorter than the arm 22 and the arm 21 extends toward the back of the box while the arm 22 extends toward the opposite end 90 of the lay beam. The arm 22 is inwardly bowed and gradually curved, and the arm 21 is also inwardly bowed, the chords of the arcs of the two arms being disposed at an angle to each other. Riveted or otherwise 95

attached to the inner face of the arms 21 and 22 is a leather strap 25. This strap is riveted to the extremity of the arm 21 by means of the rivet 26 and is also riveted at its opposite end at a point adjacent the extremity of the arm 22 by means of a rivet 27. This strap is drawn taut and bridges the triangular space 28 between the arms 21 and 22. The strap and the arm 22 are both coincidentally slotted at 29 for the usual feeler. Attached to the inner face of the arm 22 at a point just rearward of the forward extremity of the triangular space 28 is a spring 30 which is riveted or otherwise attached to the arm 20 by rivets 31, this spring being disposed in a recess formed in the inner face of the arm and running par-

allel to the arm for a certain extent and then being outwardly and rearwardly inclined at a very slight angle, as at 32, so that the extremity of the spring lies flat against the strap 25. The strap naturally maintains itself on a straight line across the triangular space 28, but the spring resists inward movement of the strap. Preferably, the ears 24 are slotted and the pin 23 or stud is adjustable in said slot so as to shift the binder inward or outward relative to the shuttle box. I have not deemed it necessary to show the feeler nor the protecting rod mechanism, nor any of the other usual parts which do not intimately coact with the binder.

In the operation of this device, when the shuttle enters the box the binder begins to check the shuttle at the point A, gradually checking it until the shuttle strikes the leather strap and forces the leather strap against the steel spring 32 at B. When the shuttle reaches the point C, the checking of the shuttle is more severe, causing the shuttle to reach its destination at point D without any rebind or bouncing. It will be noted that when the shuttle has reached its destination, the pointed forward end of the shuttle striking against the leather on the face of the arm 21 tends to force the arm 21 to move outward, which presses the arm 22 inward just enough to force the shuttle into parallel relation with the back of the shuttle box, thus giving the magazine a clear field of operation in order to change the bobbin. It will be noted that the arm 21 bears against the shuttle over a distance not more than $1\frac{1}{2}$ " from d to d in Fig. 1. This gives a very quick and easy release so that the loom when it makes its pick will throw the shuttle with very little power, and it will also be noted that as soon as the eye end of the shuttle commences to move outward under the action of a pick, the pressure of the arm 22 on the shuttle is relieved. When this binder is set, it remains in its adjusted position until it is changed, and when it is desired to use different sized shuttles, the binder is easily adjusted by loosening the binder stud 23 and moving the binder inward or outward to suit the size of the shuttle.

It will be noted also that the binder is very substantial, heavy, and has no bolts to work loose and give trouble. In actual test, the speed of a loom with this binder has been changed from 15 to 20 revolutions per minute without changing the binder in the least and without affecting the proper operation of the binder, or without causing the loom to "bang off". The binder does away with all check straps, binder springs, etc., found on the Crompton-Knowles loom and Draper loom. It places and holds the shuttle in position so that there is no break-

age of bobbins when the magazine makes its change. The shuttle does not rebind, nor does damp or dry weather affect the shuttle box. It holds the shuttle parallel and in line with the back box, giving the magazines on the Crompton-Knowles loom or the battery on the Draper loom an opportunity to make a change in bobbin without any hang up or breakage.

It will be noted that the space 28 is relatively long and that for this relatively long distance the strap 25 is unsupported save by a portion of the spring 32, so that the forward portion of the strap conforms to the curvature of the forward end of the shuttle, but the middle portion of the strap exerts relatively light pressure against the shuttle and that the shuttle will release very quickly for the reason that as soon as the shuttle commences to move out of the box under the action of the picker stick, it moves away from the face of the strap. The spring 32 increases the check on the shuttle before the shuttle reaches its destination but the shuttle reaches its destination with much more ease than it would without the spring. The curve in the strap between the point B and the point D or a little beyond the point D is such that the strap is pressed against the shuttle at this point by the spring 32. One of the great advantages of my binder is that it permits the loom to be run with a slack protector rod spring. This eliminates wear on the shuttle and this slack protector rod spring permits the binder to operate properly where the loom is running with considerable variations in speed. These advantages are secured by the fact that with my binder the shuttle requires but a slight movement in order to release.

I am aware of Patents Nos. 1,053,066 and 958,487, which show binders similar to mine, but with binders of this character, the check is very severe from the starting point until the shuttle reaches the back of the box. This causes a great wear on shuttles, binder studs, shuttle binders, protector rod springs, and protecting fingers. It also causes wear on the cam points, cam balls, lug straps, and is liable to cause breakage of the picker sticks. This is due to the fact that with binders of the character shown in these patents, a very tight protector rod spring is necessary. The shuttle illustrated in these patents does not release as easily or quickly as mine, and when the pick is made, the shuttle in leaving the box drags from a point opposite the pivotal point of the binder nearer to the forward end thereof.

I claim:

1. In a loom, the combination with a shuttle box, of a binder therefor pivotally mounted on the shuttle box and having two angularly disposed, inwardly bowed arms, and a fabric strap attached to the inner face

125

130

of said arms and extending across the triangular space defined between said arms.

2. In a loom, the combination with a shuttle box, of a binder therefor pivotally mounted on the shuttle box and having two angularly disposed, inwardly bowed arms, and a fabric strap attached to the inner face of said arms and extending across the triangular space defined between said arms, 10 and a spring attached to the inner face of one of said arms and extending outward and bearing against the inner face of the strap midway between the arms.

3. In a loom, the combination with a shuttle box, of a binder therefor having two inwardly arcuate arms of different lengths, the binder being pivotally supported at the junction of said arms, the short arm extending toward the adjacent end of the lay beam and 20 the long arm extending toward the other end of the lay beam, the chords of said arms being disposed in angular relation to each other, a strap attached at its end to the inner face of the extremity of the short arm 25 and at its other end attached to the inner face of the long arm adjacent its extremity, said strap extending across the triangular space defined between said arms, and a flat leaf spring attached to the inner face of one 30 arm and bearing against the inner face of the strap and resisting inward movement of the strap.

4. In a loom, the combination with a lay beam and shuttle box, of a binder pivotally

mounted for movement toward or from the shuttle box, the binder comprising two arcuate arms integrally connected with each other, the binder being pivoted to the inner section of the arm, and the chords of the arms being in angular relation to each other, 35 one of the arms being relatively short and extending to the end of the box and the adjacent end of the lay beam, the other arm being relatively long and extending toward the opposite end of the lay beam, a leather strap attached to the extremity of the short arm and extending over the curved inner face of the long arm and attached to the adjacent extremity thereof, said strap extending taut across the substantially triangular 40 space between said arms, and a flat spring leaf attached to the inner ends of the long arm in said triangular space and extending outward and lying flat against the inner face of the strap and resisting inward movement 45 of the strap.

5. In a loom, the combination with a shuttle box, of a binder therefor having two angularly disposed, inwardly bowed arms, and a strap attached to the inner faces of said 50 arms and extending across the triangular space defined between said arms, the binder being pivotally mounted on the shuttle box at a point substantially at the junction of the two arms.

In testimony whereof I hereunto affix my signature.

WILLIAM B. HOLT.
